UNITED STATES PATENT OFFICE.

JACOB SCHUMACHER, OF CAMDEN, NEW JERSEY.

DESIGN FOR A BANJO.

SPECIFICATION forming part of Design No. 21,057, dated September 22, 1891.

Application filed July 11, 1891. Serial No. 399,210. Term of patent 3½ years.

To all whom it may concern:

Be it known that I, JACOB SCHUMACHER, a citizen of the United States, residing at Camden, in the county of Camden and State of New Jersey, have invented and produced a new and useful Design for a Banjo-Body, of which the following is a specification, reference being had to the accompanying perspective-view drawing, forming part thereof.

My invention relates to the outline or figure of a banjo-body A, which consists in the bottom elliptical-curve line *a* and the head

circular line *b*, which are connected by the concave neck-curve lines *c*.

I claim—

The design for a banjo herein shown and described.

In testimony whereof I affix my signature in presence of two witnesses.

JACOB SCHUMACHER.
